Geo. S. Williams of Fulton Township, Ohio
Letters Patent

The Schedule referred to in the following Patent and making part
of the same containing a description in the words of the said Geo.
S. Williams himself of his improvement on the art of Road-making.

To all to whom these presents shall come, Be it known,
that I, Geo. S. Williams of Fulton Township in Hamilton Coun-
ty and State of Ohio, have invented a novel and useful improve-
ment in the art of Road-making, and that the following is
a full and exact description thereof. I prepare stone in
the usual manner for the construction of a Macadamized cover
by reducing it to particles not exceeding a specified maximum
weight or size. I then prepare the bed of the Road in the usual
manner by laying on the stone cover. But instead of making the
Macadamized cover of the usual width it is to be laid narrower
to which an edging of rough stone is general to be added to each side
to make out the intended width of cover. It is not intended to
confine the Road-making to any specific model of combining the
small stones with the rough edging but the method I prefer is this.
After the bed is prepared to receive the prepared stone, let a layer
of it be laid, but before it is rolled or trampled, let a rough edging
be laid on each side thick enough to receive the full Macadamized
cover after it is consolidated. The Macadamized cover is laid
a foot in depth, 8 or 9 inches of edging will be sufficient thickness,
which may be thinner at the extreme edges, if the edging is to be
of common flancement laid solid, no further labor will be
necessary, but if the edging is to be of smaller stones it will be need-
ful to point it with a ridge, or long handled barrow, until the top
stones are reduced to a uniform size, say not exceeding three inch-
es in greatest dimension. If the edging be of gravel it will be
necessary to lay it in layers not exceeding the thickness of the
layers of stone for the centre cover and to roll both cubic and

198.

edging simultaneously; The Telford Road is constructed by setting a thin but very rough pavement of large stone in the bottom, over which a layer of stone prepared in all respects, as for a Macadamized road is to be spread and trampled down, into a smooth surface. It is intended to combine this kind of road with rough edging in like manner and for similar purposes. In this case I should prefer to construct the rough edging first, and then have between for the reception of the prepared stone.

I do not claim as my invention the construction of either Macadamized or Telford Roads neither do I claim the paving of street gutters, where the centre is Macadamized. But what I do claim is my own invention and not previously known in the art of Road-making, is the combining or using a rough edging of any kind with a Macadamized or Telford road, the intention of constructing the rough edging being principally to make width to accommodate passing vehicles, and to give support to the edges of the smooth road to prevent the small particles of which they are composed from spreading out onto the road and weak edges.
